AUTOMOTIVE ACCESSORY

John T. Whalen, New York, N. Y.

Application November 8, 1934, Serial No. 752,105

20 Claims.

(Cl. 254—1)

The invention relates to new and useful means for use in lifting automobile axles preparatory to changing wheels and more particularly to such devices which are positioned or centered automatically by the car.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a perspective view of an embodiment of the invention in operating position;

Fig. 2 is a fragmentary elevation showing the jack positioned beneath the car axle by the action of the car wheel with the device;

Fig. 3 is a side view looking at Fig. 2 from the right;

Fig. 4 is a top plan corresponding to Fig. 1, and showing the transverse portion, which cooperates directly with the wheel, folded over on the portion connecting with the jack;

Fig. 5 is an elevation looking at Fig. 4 from the bottom, with the device completely folded together;

Fig. 6 is a detached plan of the base to which the jack is pivotally connected;

Fig. 7 is an enlarged elevation partly in section on the line 7—7 of Fig. 4;

Fig. 8 is a perspective view of a modification wherein the jack is clamped on a rotatable base plate;

Fig. 9 is a side elevation corresponding to Fig. 8;

Fig. 10 is an elevation of a modification of the wheel-engaging member;

Fig. 11 is an enlarged perspective view of the left-hand end of Fig. 10;

Fig. 12 is a plan corresponding to Fig. 11 with parts omitted;

Fig. 13 is a perspective view of a modified form;

Fig. 14 is an elevation looking at Fig. 13 from the right;

Fig. 15 shows a crutch to hold the jack cranking rod;

Fig. 16 is a perspective of said jack; and

Fig. 17 shows a modified form of the wheel-engaging device.

The invention provides means for lifting an automobile axle to change wheels wherein the jack is centered beneath the axle by the car it-

self, and the necessity of manually inserting and centering the jack beneath the axle is avoided, and in accordance with certain features of the invention the device may be set upon the ground away from the car and the car driven so that the wheel rolling upon the device automatically centers the jack, preparatory to lifting the axle and the wheel from the ground. The device of my invention is also foldable into compact form for packing or storage in the car, and is quickly and easily folded and unfolded between the operative and packing positions. In accordance with one feature of the invention, it may be embodied in a unitary device with the jack, or it may be manufactured and sold separately and used in connection with any jack. Other features of the invention will be described and pointed out hereinafter.

Referring now in detail to the embodiment of the invention illustrated by way of example in the accompanying drawings, a jack 1 is exemplarily shown having the usual longitudinally movable lifting bar 2, and suitable operating means therefor, including the rotatable socket 3 mounted on a base 4. In certain figures of the drawings the jack is shown pivotally connected to provide a unitary device with the positioning and centering means, and in other figures the device is shown attachable to and detachable from the jack, to be used with any jack, such as the jack provided with a particular car. In the first-mentioned form (Figs. 1-7), the jack is shown pivotally mounted on a base 8 by means of a pivot 9 connecting the bottom plate 4 of the jack and the base 8, the base 8 resting upon the ground or floor. By reason of the pivotal mounting, the jack can be turned so that it may be operated from the front, the rear or the side of the car.

The embodied form of means operating between the jack and a wheel whereby the wheel driven or rolled onto the device centers the jack beneath the axle, and spaces or positions the jack along the axle relatively to the wheel, is constructed so that the device is foldable into a relatively small space. As thus embodied, a flat plate or bar 11 is connected to the base 8 by means of a hinge pin 12. The member 11 is preferably variable in length to permit the jack to be positioned beneath the axle at different distances inwardly from the wheel. As embodied, the plate 11 is in two parts, the part 14, overlying the part 11, and having a longitudinally disposed slot 15 through which headed pins 16 and 17 project, the pins being fixed in the plate 11, their expanded heads holding the two plates together while permitting the longitudinal sliding action.

The embodied form of wheel-centering and holding means cooperating to center the jack beneath the axle comprises a wheel-supporting plate 21 which is mounted transversely at the

outer end of the member 14 and is provided with means for effecting the centering automatically by rolling the wheel thereonto. This mechanism is likewise shown capacitated to fold with the parts previously described into a small compass for packing. As embodied, therefore, the plate 21 is pivotally mounted upon the outer end of the plate 14, at 22, so as to be movable from the transverse operative position into direct line with 14 for folding. For further folding for the sake of compactness, plate 21 is in two parts 24 and 25, which are connected together by a hinge joint 23, near the pivot 22. A lining or positioning lugs 26 and 27 serve to hold the bar 21 in operative position. In packing, the plate 24 is turned on hinge 23 and thereby is lifted away from lug 26 and will lie upon the plate 25. The two superposed plates 24 and 25 may then be rotated about pivot 22, away from the other lug 27 and into alignment with the plate 11, 14. The folding and structure of the remaining parts will be later described. Mounted at either end of plate 21 is an upwardly extending, angular tracking, holding and centering device, the wheel riding up over an angled track at one end of plate 21, and being stopped or held between the two angled devices, and thereby held or stopped with the jack centered beneath the axle. As embodied, these functions are effected by either of the devices, either one serving to ride the wheel on or to stop it in position, the mechanism thereby being double ended. As embodied, there are two groups of plates at either end of the member 21. In both devices a short plate 29, of somewhat greater width than the plate 21 is hinged to the end of plate 21 at 30. A similar plate 31 is hinged to the opposite edge of plate 29, as shown at 32. Plate 31 is recessed at 34, and the plate 21 is correspondingly notched as shown at 35. The recess and notches hold the plates 29 and 31 in the inclined position shown in Fig. 1. If desired, a reversely inclined part 39 may be formed on plate 31 when it engages notch 35 to insure against slippage, as shown in Fig. 17. Thus the wheel will roll up over one of the devices and will drop between them and the jack is thereby automatically centered under the axle. When the device is in the position shown in Fig. 1 it can be set on the ground in the open either in front of or behind the car, and the car is driven to roll the flat wheel onto the device, as shown in Fig. 2, and thus by merely driving the car forward or backward, the wheel will roll over one of the projections 29, 31 and will be stopped by the other, and thereby the jack 1 will be centered and firmly held beneath the axle, as already described. The actuating rod 36 may then be inserted in socket 3 to operate the jack in the usual manner to lift the axle and wheel for changing. The swivel mounting of the jack permits the device to be used for either a front or rear wheel. Before the jack is lowered one set of plates 29, 31 can be folded out flat preparatory to the wheel rolling off on that side.

The folding of the device as embodied for packing is shown in Figs. 4 and 5. Referring to Fig. 1, the left-hand plate 31 is lifted from one set of notches 35 and is folded flat upon the member 24. In like manner the plates 29, 31 at the right-hand end in Fig. 1 are folded flat down upon the bar 25. The bar 24 is then rocked upwardly about hinge 23, is freed thereby from lug 26 and is laid down on top of the member 25 and on the right-hand extended plates 29, 31. These parts

so folded are then rotated about the pivot 22, away from the other lug 27, until they are in line with the connecting member 11, as shown in Fig. 4. The member 11 and all the superposed parts folded over thereon are then rocked upwardly about the hinge 12 into the position shown in Fig. 5, the device thereby being folded into a relatively small and compact space.

In Figs. 8 and 14 are shown certain modifications, which will now be described, it being understood, however, that these modifications are illustrative only, and are not exhaustive of the changes that may be made in the device as covered by the claims. In Figs. 8 and 9, the jack 1 is shown separable. A base 41 corresponding to the base 4 is pivotally mounted at 42 upon the base plate 8, the jack being clamped by its base 43 to the plate 41. For the purpose of holding jacks having bases of different sizes and centering the jack with the device irrespective of such difference in size, a set of clamps 47 are provided, each clamp having a universal adjustment. As embodied, the plate 41 has upturned lips or edges 53 and 54 at the front and rear. Longitudinal slots 55 are formed in the lips and corresponding longitudinal slots 56 are formed in the plate 41. The angled clamps 47 have fingers 59 which project into the corresponding slot 55 and the clamps have also a finger 60 which projects into the corresponding slot 56, as shown in Fig. 8. Clamping bolts 63 project through slots 64 formed in the overhanging part of the clamps 47, these bolts having nuts 66 threaded thereon beneath the clamp 47, whereby the ends of the bolts may be screwed down to clamp the jack base to plate 41. The bolts 63 are movable longitudinally in their slots 64 to position them for different size bases. Thus a jack of any sized base may be centered on the device and firmly held in that position.

In Figs. 10, 11 and 12 the wheel-centering device is shown with a very wide range of size variation. In this form the plates 24 and 25 have corresponding extensions 24a and 25a, and these extensions have additional notches 35 near their outer ends. The plates 29 and 31 may thus be turned either inwardly or outwardly as shown in said figures to provide a greater or less space between them to accommodate wheels of different sizes.

In Figs. 13 and 14 a modification is shown wherein the jack is operated from the side as distinguished from the usual operation from the front or rear. As here shown, the jack is operated by a rod 71 which is universally jointed as shown at 72, 73 and 74, and the rod is housed within a box 75 fixed upon the plate 25. A double hinge is provided at 71 to permit the member 24 to fold over the box 75 for packing.

In Figs. 15 and 16 is shown a crutch 81 for holding the jack crank or actuating rod 36 from tipping to the ground and tilting the wheel engaging device. With this means, the jack crank may be inserted in the jack before the wheel is driven on. The crutch 83 has an orifice 84 through which the jack crank rod 36 is passed, and it has legs 85 and 86 which rest upon the ground.

The invention in its broader aspects is not limited to the details of construction shown and described in connection with the present preferred embodiment, but changes may be made therein within the scope of the accompanying claims without departing from the principles of the invention or sacrificing its chief advantages.

What I claim is:

1. A device for centering a lifting jack beneath an automobile axle including in combination a member connectable to a jack, a member connected to said first-named member and extending in the direction of the wheel and means pivotally mounted thereon for engaging the automobile wheel at either side of its bottom point to center it and aline the jack beneath the axle, said pivotally-mounted means having downwardly and outwardly inclined faces for acting as ramps to facilitate positioning of the wheel.

2. A lifting jack centering device adapted to be set on the ground before or behind an automobile and including in combination a member connectable to a jack and a member connected to said first named member and upon which an automobile wheel is rolled, said member having pivoted thereto projections over one of which the wheel rolls and by the other of which it is stopped to center the wheel and aline the jack beneath the axle, means for holding said projections in elevated position during engagement of the wheel, the projections being movable from said elevated position to release the wheel or to facilitate packing.

3. A lifting jack centering device adapted to be set on the ground before or behind an automobile and including in combination a member rotatably connectable to a jack and extending in the direction of the axle, a member connected to said first named member and extending in the direction of the wheel and onto which the wheel may be rolled, said member having projections over one of which the wheel rolls and by the other of which it is stopped to center the wheel and aline the jack beneath the axle, at least one of said projections being movable relative to said member to facilitate movement of the wheel and packing of the device.

4. A lifting jack centering device adapted to be set on the ground before or behind an automobile and including in combination a member connectable to a jack and a member connected to said first named member and upon which an automobile wheel is rolled, said member having pivoted thereto projections over one of which the wheel rolls and by the other of which it is stopped to center the wheel and aline the jack beneath the axle one of said projections being collapsible preparatory to rolling the wheel off from the device.

5. A device for centering a lifting jack beneath an automobile axle including in combination a member rotatably connectable to a jack and extending in the direction of the axle, a member connected to said first named member and extending in the direction of the wheel and having elevated means for engaging with the wheel to center it and aline the jack beneath the axle, said elevated means being foldable for compact packing, and means for holding said means in elevated position to engage the wheel.

6. A device for centering a lifting jack beneath an automobile axle including in combination a jack, a member connected thereto and extending in the direction of the axle, a member connected to said first named member and extending in the direction of the wheel and having means for engaging with the wheel to center it and aline the jack beneath the axle, said means being movable into elevated position to engage the wheel and movable out of said position.

7. An apparatus for centering a lifting jack beneath an automobile axle including in combination a device connectable to a jack, a connecting

member extending therefrom along the axle, and a wheel-engaging member attached to said connecting member and movable into transverse position to be engaged by the wheel to center the jack under the axle and movable into alinement with said connecting member for packing.

8. An apparatus for centering a lifting jack beneath an automobile axle including in combination a device connectable to a jack, a connecting member extending therefrom along the axle, and a wheel-engaging member attached to said connecting member and movable into transverse position to be engaged by the wheel to center the jack under the axle and movable into alinement with said connecting member for packing, said wheel-engaging member being medianly hinged to fold upon itself.

9. A device for centering a lifting jack beneath an automobile axle including in combination a jack, a member extending from the jack, a member connected to said first-named member and adapted to be engaged by the wheel to center the jack under the axle, said first-mentioned member being foldable alongside the jack for packing, and said second member being movable into alinement with said first-mentioned member for packing.

10. A device for centering a lifting jack beneath an automobile axle including in combination a jack, a member extending from the jack, a member connected to said first-named member and adapted to be engaged by the wheel to center the jack under the axle, said first-mentioned member being foldable alongside the jack and said two members being movable into alinement for packing.

11. A device for centering a lifting jack beneath an automobile axle including in combination a jack-supporting base and means for pivotally mounting the jack thereon, a spacing bar pivotally connected to the base and means for varying the length of said spacing bar, wheel centering and holding means comprising a wheel supporting plate pivotally connected centrally to the other end of said spacing and centering bar, said wheel supporting plate being in two parts, hinged together near said pivot connection, and at either end of said wheel supporting plate a tracking, holding and centering device, each of said devices comprising a plate hinged to the end of said wheel supporting plate, a third plate hinged to the outer end of said second plate, and means for holding said second and third plates in elevated angled position upon said wheel supporting plate at either end thereof, and for packing, the plates of said tracking, holding and centering devices being foldable flat upon said wheel supporting plate, the wheel supporting plate being foldable upon itself and swingable in its folded position into line upon said spacing bar, and said spacing bar and base being foldable toward each other irrespective of whether the jack is mounted on the base or has been removed.

12. A device for centering a lifting jack beneath an automobile axle including in combination a jack-supporting base, a spacing and centering bar pivotally connected to the base and means for varying the length of said spacing bar, wheel centering and holding means comprising a wheel supporting plate pivotally connected centrally to the other end of said spacing and centering bar, said wheel supporting plate being in two parts, hinged together near said pivot connection, and at either end of said wheel supporting plate a tracking, holding and centering device,

- each of said devices comprising a plate hinged to the end of said wheel supporting plate, a third plate hinged to the outer end of said second plate, and means for holding said second and third plates in elevated angled position upon said wheel supporting plate at either end thereof, and for packing, the plates of said tracking, holding and centering devices being foldable flat upon said wheel supporting plate, the wheel supporting plate being foldable upon itself and swingable in its folded position into line upon said spacing bar, and said spacing bar and base being foldable toward each other irrespective of whether the jack is mounted on the base or has been removed.
15. A device for centering a lifting jack beneath an automobile axle including in combination a jack-supporting base and means for pivotally mounting the jack thereon, a spacing and centering bar pivotally connected to the base, wheel centering and holding means comprising a wheel supporting plate pivotally connected centrally to the other end of said spacing and centering bar, said wheel supporting plate being in two parts, hinged together near said pivot connection, and at either end of said wheel supporting plate a tracking, holding and centering device, each of said devices comprising a plate hinged to the end of said wheel supporting plate, a third plate hinged to the outer end of said second plate, and means for holding said second and third plates in elevated angled position upon said wheel supporting plate at either end thereof, and for packing, the plates of said tracking, holding and centering devices being foldable flat upon said wheel supporting plate, the wheel supporting plate being foldable upon itself and swingable in its folded position into line upon said spacing bar, and said spacing bar and base being foldable toward each other irrespective of whether the jack is mounted on the base or has been removed.
14. A device for centering a lifting jack beneath an automobile axle including in combination a jack-supporting base, a spacing and centering bar pivotally connected to the base, wheel centering and holding means comprising a wheel supporting plate pivotally connected centrally to the other end of said spacing and centering bar, said wheel supporting plate being in two parts, hinged together near said pivot connection, and at either end of said wheel supporting plate a tracking, holding and centering device, each of said devices comprising a plate hinged to the end of said wheel supporting plate, a third plate hinged to the outer end of said second plate, and means for holding said second and third plates in elevated angled position upon said wheel supporting plate at either end thereof, and for packing, the plates of said tracking, holding and centering devices being foldable flat upon said wheel supporting plate, the wheel supporting plate being foldable upon itself and swingable in its folded position into line upon said spacing bar, and said spacing bar and base being foldable toward each other irrespective of whether the jack is mounted on the base or has been removed.
15. A device for centering a lifting jack beneath an automobile axle including in combination a jack-supporting base, a spacing and centering bar pivotally connected to the base, wheel centering and holding means comprising a wheel supporting plate pivotally connected centrally to the other end of said spacing and centering bar, and at either end of said wheel supporting plate a tracking, holding and centering device, said devices comprising plates pivotally connected together and to said wheel supporting plate, and adapted to project upwardly at either end of the wheel supporting plate and to lie along it for packing.
16. A device for centering a lifting jack beneath an automobile axle including in combination a jack-supporting base, a spacing and centering bar pivotally connected to the base, wheel centering and holding means comprising a wheel supporting plate pivotally connected centrally to the other end of said spacing and centering bar, and at either end of said wheel supporting plate a tracking, holding and centering device, said devices comprising plates pivotally connected together and to said wheel supporting plate, and adapted to project upwardly at either end of the wheel supporting plate and to lie along it for packing.
17. A device for centering a lifting jack beneath an automobile axle including in combination a jack-supporting base, a spacing and centering bar connected to the base, wheel centering and holding means comprising a wheel-supporting plate pivotally connected centrally to the other end of said spacing and centering bar and at either end of said wheel supporting plate a tracking, holding and centering device, said devices comprising plates pivotally connected together and to said wheel supporting plate, and adapted to project upwardly at either end of the wheel supporting plate and to lie along it for packing.
18. A device for centering a lifting jack beneath an automobile axle including in combination a member connectable to a jack, and a connected member engaged by the automobile wheel to center it substantially at ground level and align the jack beneath the axle, said connected member comprising a thin flat plate for underlying the wheel on the ground and having spaced-apart elevations between which the wheel is engaged.
19. A device for centering a lifting jack beneath an automobile axle including in combination a member connectable to a jack, and a permanently connected member engaged by the automobile wheel to center it and align the jack beneath the axle said member having spaced-apart elevations between which the wheel is engaged, with downwardly and inwardly inclined surfaces to hold and center the wheel and with downwardly and outwardly inclined surfaces to act as ramps in positioning the wheel.
20. A device for centering a lifting jack beneath an automobile axle including in combination a member connectable to a jack, and a connected member engaged by the automobile wheel to center it and align the jack beneath the axle, said member having spaced-apart elevations between which the wheel is engaged, at least one of said elevations being collapsible to facilitate movement of the wheel onto or off the member.

JOHN T. WHALEN.
